CLAMPING DEVICE

George Paul Rinker, Brooklyn, and Russel Parry Miller, Indianapolis, Ind., assignors to Line Material Company, Milwaukee, Wis., a corporation of Delaware

Application April 23, 1941, Serial No. 389,902

6 Claims. (Cl. 24—134)

This invention relates to devices for releasably gripping and holding under tension a steel cable or the like; and it has for its principal object to provide a device of that character which will grip a cable more securely but with less tendency to injure the cable than other devices of its kind heretofore employed.

Another object is to provide a device of the above description which is capable of use with cables having a substantial range of diameters without the necessity of employing a different set of jaws for each size of cable.

The novel features of our invention can be indicated most readily in conjunction with the drawings and detailed description which follows:

In the drawings:

Fig. 1 is an elevational view, partly in section, depicting a releasable cable-gripping and holding device in accordance with a preferred embodiment of our invention—the device being illustrated in gripping engagement with a cable and attached to a fixed support.

Fig. 2 is a top plan view, of the device.

Figs. 3 and 4 show the gripping surfaces of the jaws shown in Fig. 1.

Fig. 5 is an enlarged sectional view taken on the line 5—5 of Fig. 1.

Identical parts are designated by the same reference numerals throughout the several views.

The clamping device illustrated includes a link member 10 pivotally secured to an eye-bolt 13 by means of a pin 14 which is held in place by a cotter pin 15.

Eye-bolt 13 is secured to any suitable support, as for example an electric transmission pole 16 fragmentarily shown.

Link member 10 is formed, intermediately of its ends with a hook 18 for purposes hereinafter explained.

A jaw-supporting element includes a pair of spaced side members 21 disposed in mutually parallel relationship and joined by a cross-rib 22 which is cast integrally with the side members.

Said jaw-supporting element is pivotally connected to link 10 by means of a pin 24 which is locked in place by a cotter pin 24A.

A jaw 29 is pivotally connected to the jaw-supporting element by means of a pivot pin 27; and a jaw 30 is similarly connected to said element by means of a pin 28. The two jaws are rotatable about their respective pivots.

Jaw 29 has a reinforcing web 35 and is formed at one end to provide a cable-guide channel 33—which is defined by two spaced complementary flanges 34. The upper end of the said jaw 29 has

an elongated cable-gripping surface 31 which is convexly arcuate in a plane transverse to the axis of pivot pin 27, as shown in Fig. 1—said surface being concave in cross section as illustrated in Fig. 5. The cable-gripping surface of jaw 29 merges into cable-guide channel 33 and forms a continuation thereof. Jaw 30 has a reinforcing web 39 and has an elongated cable-gripping surface 37 which is concavely arcuate in a plane transverse to the axis of pivot pin 28, as shown in Fig. 1—said surface 37 being concave in cross section as illustrated in Fig. 5.

The two cable-gripping jaw surfaces 31 and 37 are mutually in face-to-face relation and are approximately parallel when engaging a cable as shown. The two jaw surfaces define, conjointly, a channel substantially embracing the cable 42 and the two jaws function conjointly to grip the cable when tension is applied to the cable in the direction indicated by arrow A, Fig. 1.

If the two jaws are rotated in a clockwise direction, as viewed in Fig. 1, their respective cable-gripping surfaces will separate to a limited extent. Likewise, if said jaws are rotated in a counter-clockwise direction as viewed in Fig. 1, the cable-gripping surfaces will move toward each other. Hence, it will be apparent that the device is capable of use with cables having a substantial range of diameters—although not adapted, with a single pair of jaws, for use with cables of widely varying diameters.

The cable-gripping surfaces 31 and 37 are preferably provided with angularly extending grooves 32 and 38 in approximate conformity with the angularly extending strands of the cable. The cable strands tend to seat themselves in said grooves, thereby increasing the grip of the jaws on the cable.

It will be apparent that when tension is applied to the cable, as indicated, jaw 29 will be rotated about its pivot in a manner tending to close the gap between the two cable-gripping surfaces and that the cable will be gripped between the jaws along a surface of considerable length—instead of being gripped at a single point. The elongated gripping surfaces serve to obviate crimping of the cable and to prevent the jaws biting into the cable excessively.

In order to apply adequate torque to jaw 29 as a result of tension on the cable, it is important that the pivotal center of said jaw be laterally offset from the axis of the tensioned portion of the cable to such an extent as to provide an effective moment of force. Obviously, the greater the perpendicular distance from the center of

pin 27 to the projected axis of the tensioned portion of the cable, the greater will be the moment of force for a given applied tension and, correspondingly, the greater will be the gripping force applied to the cable. For that reason jaw 29, as shown, is considerably longer from its pivotal center to the cable-guide end than from the pivotal center to the other end. This is not essential to the operativeness of the device, but it contributes greatly to the effectiveness of the jaws to provide for an ample moment of force. Manifestly, it is not of the essence of the invention that jaw 29 be asymmetrical, as shown in Fig. 1.

If the device is applied to a smaller cable than that shown, the jaws will rotate counterclockwise, as viewed in Fig. 1, in order to adjust themselves to the smaller cable, and that results in a diminution of the lever arm and a consequent diminution of the moment of force—if a given cable tension is assumed. But an increase in the diameter of the cable will have the opposite effect. In designing a device in accordance with this invention, the aforementioned factors should be kept in mind.

Link 10 is not an indispensable element, but it serves as a convenient means for adequately spacing the jaws from the fixed support 16 and also as a convenient means for attaching a block and tackle. In connecting the cable to our gripping and holding device it is the usual practice to attach to the cable, temporarily, a suitable clamp to which one end of the block and tackle can be fastened, and the other end of the block and tackle is connected to hook 18. The cable is then put under tension by means of the block and tackle and the loose end 43 of the cable is threaded between jaws 29 and 30; and a man throws his weight on the dependent cable end while the block and tackle is being released. Tension of the cable then automatically causes jaw 29 to rotate and gripping engagement of the cable between the jaw surfaces is immediately effected.

The point of attachment of the jaw-supporting element to the fixed support which, in the case illustrated, is pin 24, should be remote and laterally displaced from a plane parallel to and intersecting the axes of the two pivot pins 27 and 28—in order to obtain adequate leverage on jaw 29. This rule is applicable, of course, only when the jaw-supporting element is pivotally connected to its support as here depicted. Manifestly, the pivotal attachment makes it possible to run the cable at any desired angle to the fixed support, which, obviously, would not hold true if the jaw-supporting element were rigidly mounted.

When it is found to be desirable to change the size of wire or cable on an electric transmission line, or remove the cable 42 for any reason from its gripped position, the removal is easily and quickly accomplished by reversing the mounting operation hereinbefore described. A block and tackle is attached to the cable and hook 18 and the tension relieved from the jaws, thereby enabling the operator to remove from place the cotter pin 45, pin 27, and jaw 29. In this manner the cable is quickly and easily lowered without interference from the jaws which if in place would tend to grip the cable during the removal operation.

From the foregoing description it is obvious that the objects of this invention have been accomplished by providing a clamping device hav-

ing pivotally mounted, removable jaws automatically coacting to provide a uniform grip on a cable held therebetween and to provide a quick and simple manner of connecting and disconnecting a cable therewith.

Further objects have been accomplished by providing jaws relatively pivoted with respect to the direction of cable pull so as to be rotated into a plurality of various cable openings whereby various size cables may be effectively held without the angle of the jaws to the direction of wire pull being changed enough to prevent gripping.

We claim:

1. In a device for releasably gripping and holding under tension a cable or the like, the combination comprising a jaw-supporting element, a pair of co-operating clamping jaws pivotally connected to said element and carried thereby, the pivotal axes of said jaws being parallel and spaced apart laterally, each of said jaws having an elongated cable-gripping surface which is arcuate in a plane transverse to its pivotal axis, one of said surfaces being convexly arcuate in said plane, the other of said surfaces being concavely arcuate in said plane, said surfaces being spaced apart laterally and disposed mutually in face-to-face relation, the elongated arcuate contours of said surfaces being approximately parallel when a cable or the like is gripped therebetween.

2. In a device for releasably gripping and holding under tension a cable or the like, the combination comprising a jaw-supporting element and a pair of cable-gripping jaws carried by said element, at least one of said jaws being movable relatively to the other for gripping and releasing a cable therebetween, said jaws having elongated cable-gripping surfaces which are of arcuate contour lengthwise of the cable-portion therebetween, said surfaces being complementarily convex and concave respectively, said device including cable-actuated lever means for pressing said surfaces into conjoint gripping engagement with the cable, said lever means being responsive to tension applied to the gripped cable to effect and vary proportionately to said tension, the tenacity of said gripping engagement.

3. In a device for releasably gripping and holding under tension a cable or the like, the combination comprising a jaw-supporting element and a pair of cable-gripping jaws carried by said element, at least one of said jaws being movable relatively to the other for gripping and releasing a cable therebetween, said jaws having cooperative cable-gripping surfaces which are elongated lengthwise of the cable-portion gripped therebetween and operative to grip the cable throughout an elongated area, said device including lever means operable by the cable gripped between said surfaces to effect cable-gripping actuation of said device in response to tension applied to said cable and further operative to vary proportionately to the tension applied to said cable the tenacity of the grip of said jaws on the cable.

4. In a device for releasably gripping and holding under tension a cable or the like, the combination comprising a jaw-supporting element, a pair of co-operating clamping jaws pivotally connected to said element and carried thereby, the pivotal axes of said jaws being parallel and spaced apart laterally, each of said jaws having an elongated cable-gripping surface which is arcuate in a plane transverse to its pivotal axis

and concavely grooved in a plane normal to its length, one of said surfaces being convexly arcuate in said first-mentioned plane, the other of said surfaces being concavely arcuate in said first-mentioned plane, said surfaces being spaced apart laterally and disposed mutually in face-to-face relation, the elongated arcuate contours of said surfaces being substantially parallel when a cable or the like is gripped therebetween, said jaws being operative, conjointly, to grip a cable or the like throughout a substantial length thereof.

5. In a device for releasably gripping and holding under tension a cable or the like, the combination comprising a jaw-supporting element, a pair of co-operating clamping jaws pivotally connected to said element and carried thereby, the pivotal axes of said jaws being parallel and spaced apart laterally, each of said jaws having an elongated cable-gripping surface which is arcuate in a plane transverse to its pivotal axis, one of said surfaces being convexly arcuate in said plane, the other of said surfaces being concavely arcuate in said plane, said surfaces being spaced apart laterally and disposed mutually in face-to-face relation, the elongated arcuate contours of said surfaces being approximately parallel when a cable or the like is gripped therebetween, a coupling pin carried by said jaw-supporting element, the axis of said coupling pin

being parallel to the pivotal axes of said jaws and displaced laterally from a plane intersecting the pivotal axes of said jaws, said coupling pin being adapted for connecting said element to a support.

10 6. In a device for releasable gripping and holding under tension a cable or the like, the combination comprising a jaw-supporting element, a pair of cooperating clamping jaws pivotally connected to said element and carried thereby, the pivotal axes of said jaws being parallel and spaced apart laterally, each of said jaws having an elongated cable-gripping surface which is arcuate in a plane transverse to its pivotal axis, one of said surfaces being convexly arcuate in said plane, the other of said surfaces being concavely arcuate in said plane, said surfaces being spaced apart laterally and disposed mutually in face-to-face relation, the elongated arcuate contours of said surfaces being approximately parallel when a cable or the like is gripped therebetween, and a supporting link having one end pivotally connected to said element at a point laterally displaced and remote from a plane parallel to and intersecting the pivotal axes of said jaws, the other end of said link being arranged for connection to a fixed support.
